UNITED STATES PATENT OFFICE.

GEORGE L. THOMPSON, OF CHICAGO, ILLINOIS.

CURLING-IRON.

SPECIFICATION forming part of Letters Patent No. 404,127, dated May 28, 1889.

Application filed July 24, 1888. Serial No. 280,893. (No model.)

To all whom it may concern:

Be it known that I, GEORGE L. THOMPSON, of Chicago, in the county of Cook and State of Illinois, have invented certain new and useful Improvements in Curling-Irons; and I do hereby declare that the following is a full, clear, and exact description thereof, reference being had to the accompanying drawings, and to the letters of reference marked thereon, which form a part of this specification.

This invention relates to an improvement in curling-irons of that class embracing a cylindric metal rod or mandrel provided with a handle at one end, and which is used by heating the mandrel and then wrapping the hair about the same.

The invention embraces an improved means for connecting the metal mandrel with the handle, whereby the transmission of heat from the mandrel to the handle is prevented or lessened, and it also embraces an improved construction in a spring-clasp for clasping the end of the lock of hair to the outer surface of the mandrel to facilitate the holding of the hair while being wound thereon.

A curling-iron embodying the main or principal features of my invention is provided with a handle, a mandrel, and a tube connecting the handle and mandrel, such tube-connection preventing the passage of the heat from the mandrel to the handle, while at the same time affording a suitably-rigid connection between the parts and giving a neat finish to the article as a whole.

In the accompanying drawings, illustrating my invention, Figure 1 is a side view of a curling-iron embodying the main features of my invention. Fig. 2 is a central longitudinal section thereof. Fig. 3 is a detail sectional view showing a modified form of the recessed connection wherein the latter consists of a tube provided with a non-conducting filling.

As illustrated in Figs. 1 and 2, A is a mandrel, preferably made solid and of metal and cylindric in form.

B is a handle; C, a tube connecting the mandrel and the handle; D, a spring-clasp, pivoted by means of a pivot-pin, d, to the tube C, and provided with a thumb-piece or handle, D', to which is attached a leaf-spring, d', which

bears upon the adjacent surface of the tube and tends to hold the clasp in contact with the mandrel. The tube C is desirably made of the same exterior diameter as the mandrel, 55 and is fitted over the end of said mandrel and secured thereto by a rivet, e, in a manner clearly shown in Fig. 2. A screw-joint or other connection may, however, be made between the parts with practically the same 60 result. Said tube is shown as secured to the handle by rivet e; but any other convenient means for connecting these parts may be used in practice, as desired.

The purpose of the tube C connecting the 65 mandrel and the handle is to prevent the transmission of the heat to the handle when the mandrel is heated for curling the hair, it being entirely obvious that if the mandrel were made in one solid piece of metal reaching 70 to or into the handle, as similar curling-irons have been heretofore made, the heat would be rapidly transmitted to the handle, thereby making the same uncomfortably warm for the hand, or might char the handle. The said 75 tube C illustrated is shown as provided with a number of air holes or apertures, c² c² c², which lessen the area of the tube through which heat may be transmitted, and serve to admit air to the interior of the tube, thereby 80 tending to keep the latter cool.

The pivot d of the spring-clasp D is illustrated as inserted through the tube C, and the spring d' as arranged to bear upon said tube. The said spring is arranged to engage 85 the tube, instead of the mandrel proper, in order that the spring may be heated as little as possible. It is specially desirable that the spring should come in contact with the tubular part only, for the reason that in case that 90 spring is in direct contact with the mandrel the heat of the latter is liable to transmit to the spring a sufficient quantity of heat to affect its temper.

The employment of a tube as a means of 95 connecting the mandrel and the handle possess important advantages in point of neatness and smoothness of finish and cheapness of manufacture, and an implement constructed with a tubular connecting part is 100 therefore herein specifically claimed as part of my invention.

The hair-curler constructed as above described is employed in the usual manner by first heating the mandrel to a desired temperature and clasping the end of the lock of hair between the spring-clasp and the mandrel, and thereafter revolving the handle so as to coil or wrap the hair about the mandrel and clasp. The said clasp shown in Figs. 1 and 2 is desirably made of sheet metal bent 5 into concave form to fit the surface of the mandrel and having downwardly-bent marginal ears d^2 to receive the pivot-pin d .

I have herein shown the mandrel of the curling-iron as being made solid and of metal. 15 Such mandrel may, however, be constructed entirely of other substance—as, for instance, soapstone—or it may be tubular and of sufficient thickness to retain heat a suitably long time for effective use; or it may be a thin 20 metal tube provided with a filling of pulverized refractory material, such as has heretofore been used for similar purposes.

The construction herein described relating 25 to the means for connecting the mandrel which is to be heated with a handle may be employed as well in connection with the metal rod or core of the curling-iron shown in prior Letters Patent, No. 361,682, issued to Rufus P. Dunn April 26, 1887, (embracing in 30 connection with said core a metal tube in which the core is inserted,) as to the particular form of curling-iron herein illustrated.

In Fig. 3 of the drawings I have illustrated another construction in a connection between 35 the mandrel and handle, in which a non-perforated tube, C, is employed, such tube being provided with a filling, C', of asbestos or other similar substance having little capacity for conducting heat.

40 As a further and separate improvement in curling-irons having spring-clasps, I place between the handle D' of the clasp and the spring d' a piece or layer, d^2 , Fig. 2, of asbestos paper or other material which is a 45 non-conductor of heat, such layer preventing

the rapid passage of heat from the handle to the spring. The rivet which secures the spring to the handle is shown as passing through the said layer, thereby holding the same from displacement. The spring being 50 arranged to rest on the tube C and the clasp being pivoted to the said tube, the only way in which the spring can become heated is by the conduction of heat through the handle of the clasp, and the passage of heat to the 55 spring through said handle is prevented by the said non-conducting piece or layer d^2 , above described.

I claim as my invention—

1. As a novel article, a curling-iron consisting of a mandrel, a handle, and a tube for uniting the handle and mandrel, said tube being attached to the handle and fitted over the end of the mandrel and permanently secured thereto, substantially as described. 60

2. As a novel article, a curling-iron consisting of a mandrel, a handle, and an apertured tube for uniting the handle and mandrel, which is attached to the handle and is fitted over the end of the mandrel and permanently 70 secured thereto, substantially as described.

3. A curling-iron comprising a mandrel, a handle, a tube connecting the same, and a spring-clasp pivoted to the said tube, substantially as described. 75

4. The combination, with a mandrel and a handle, of a tube connecting the handle and mandrel, a spring-clasp pivoted to said tube, a leaf-spring attached to the handle of the clasp and bearing on the tube, and a piece or layer of non-conducting material placed between the handle and spring, substantially as described.

In testimony that I claim the foregoing as my invention I affix my signature in presence 85 of two witnesses.

GEORGE L. THOMPSON.
